UNITED STATES PATENT OFFICE.

FRANK MACK, OF NEW YORK, N. Y.

DESIGN FOR A HAT-LINING.

SPECIFICATION forming part of Design No. 31,423, dated August 15, 1899.

Application filed July 1, 1899. Serial No. 722,610. Term of patent 14 years.

To all whom it may concern:

Be it known that I, FRANK MACK, a citizen of the United States, residing at New York, in the county of New York and State of New York, have invented and produced a new and original Design for Hat-Linings, of which the following is a specification, reference being had to the accompanying drawings, forming a part thereof, of which—

10 Figure 1 is an inside or plan view showing my newly-designed hat-lining, and Fig. 2 a section thereof on the line 2 2.

As shown in the drawings, the leading or material feature of my design consists of the lining A, provided with a central picture-frame B, the lining around said frame being

of sufficient width to fill the crown of the hat in the usual manner.

Having fully described my invention, I claim as new and desire to secure by Letters ²⁰ Patent—

The design for a hat-lining herein shown and described.

In testimony that I claim the foregoing as my invention I have signed my name, in presence of the subscribing witnesses, this 20th day of June, 1899.

FRANK MACK.
